UNITED STATES PATENT OFFICE

RAGNAR TANBERG, OF PITTSBURGH, PENNSYLVANIA, ASSIGNOR TO WESTINGHOUSE ELECTRIC & MANUFACTURING COMPANY, A CORPORATION OF PENNSYLVANIA

HIGH VOLTAGE TESTING SYSTEM

Application filed March 6, 1929. Serial No. 344,851.

My invention relates to high-voltage testing systems and more particularly to methods of and means for applying high voltages to test circuits at accurately predetermined instants of time.

Heretofore, mechanical switching equipments have been used for this purpose but they have an inherent inaccuracy by virtue of the fact that the striking distance between the moving contacts varies, as well as the conditions surrounding them, such as, the degree of ionization of the air and the like which precludes consistent accuracy in applying high voltages to test circuits at predetermined instants of time.

The object of my invention is to provide a method of and means for the application of a high voltage to a test circuit at an accurately predetermined instant of time, with a consistent accuracy in the order of microseconds that is impossible to accomplish by means of mechanical switching equipment.

My invention may be more readily understood if the accompanying drawing is referred to in connection with the following description.

The single figure of the drawing is a schematic diagram of a system constructed in accordance with my invention.

A vacuum tube 1, having the usual heated filament 2, grid 3 and plate 4 housed in an evacuated tube, has its filament 2 and plate 4 connected, by conductors 6 and 7, respectively, to spark-gap electrodes 8 and 9. The grid 3 of the tube 1 is connected, by a conductor 10, to a switch 11 which is provided with a contact 12 and a contact 13. The contacts 12 and 13 are connected, respectively, to the positive and the negative terminals of a "B" battery 14 by conductors 15 and 16. The filament 2 is connected, by conductor 17, to one of the mid-connectors 18 of the battery 14.

The filament 2 is heated, in the usual manner, by any direct-current source (not shown).

The spark-gap electrodes 8 and 9 are in series with another spark-gap electrode 20 that may be provided with a condenser 21 in parallel-circuit relation with it and the

electrode 9. The spark-gap electrodes 8 and 20 are connected, by conductors 22 and 23, to condensers 24 and a test circuit, in the present case, a resistor 25. The condensers 24 are charged, by any suitable means, to a high value of voltage, say to the magnitude of 15,000 volts or more. A conductor 26, connected between the condensers 24 and the resistor 25, completes a series-circuit relation of the condensers 24, the spark-gaps 8-9 and 9-20 and the resistor 25. The latter is grounded at 27 for safety.

The distances between the spark-gap electrodes 8, 9 and 20 are so set that they just do not spark over at the voltage distribution produced by the capacity and leakage of the condenser 21 and the capacity and conductance between filament 2 and plate 4, with the filament heated and the switch 11 connected to the contact 13, thereby applying a negative bias on the grid.

By throwing the switch 11 to touch the contact 12, positive bias will thereby be placed on the grid of the tube. This increases the conductance of the tube, whereby the impressed voltage across the spark-gap electrodes 9 and 20 increases and causes the latter to break down. The breakdown of the gap between the terminals 8 and 9 will follow immediately, thereby impressing the high voltage of the condensers 24 directly upon the test resistor 25.

In this manner, a high voltage is applied to the test circuit at an accurately predetermined instant, with a consistent accuracy in the order of microseconds, which high degree of accuracy, as pointed out above, has heretofore been impossible to obtain with mechanical switching arrangements.

In some cases, where a very high voltage is to be applied to the test circuit 25, it may be necessary to use a condenser 28 (shown in dotted lines) across the electrodes 8 and 9, to which the filament 2 and the plate 4 are connected. This limits the potential across the elements of the tube to values which may be safely applied to commercial tubes. The ordinary commercial tubes will stand about 15,000 volts although some are built to stand 100

50,000 volts, but the expense of these make it desirable to use the lower-voltage tubes.

Also the condenser 21 may be made of a very small capacity or omitted entirely, when very high voltages are used in the test circuit and the voltage across the tube is to be limited, the voltage across the spark-gap electrodes varying inversely as the capacity of the condensers.

10 Various changes may be made in my invention without departing from the spirit thereof, as set forth in the following claims.

I claim as my invention:

1. The combination with a test circuit and 15 a source of high voltage, of means for impressing said voltage on said test circuit at an accurately predetermined instant of time, said means including a spark gap, and a thermionic tube for changing the voltage across said spark gap to cause it to break down.

2. In combination, a source of high voltage, a test circuit, a plurality of spark gaps in series-circuit relation with said source and 25 said circuit, a condenser across one of said gaps, and means across another of said gaps for changing the voltage across said gaps and causing said condenser to discharge across its gap, thereby causing said other gap to break down.

3. In combination, a plurality of spark gaps, a thermionic tube having its filament and plate connected across one of said gaps, and means for changing the grid bias of said 35 tube, thereby changing the voltage distribution of said spark gap.

4. In combination, a plurality of spark gaps, a thermionic tube having its filament and plate connected across one of said gaps, 40 and means for changing the grid bias of said tube from negative to positive, thereby changing the conductance between the plate and filament across said spark gap.

5. In combination, a circuit having high- 45 voltage source and a plurality of separated spark-gap electrodes in circuit relation therewith, a condenser across two of said electrodes, a circuit including the plate and filament of a thermionic tube across two of said 50 electrodes, and means for changing the grid bias of said tube from negative to positive, thereby charging said first named condenser to a value whereby it discharges across said first named electrodes, followed by the immediate discharge across said spark-gap electrodes.

6. The combination with a voltage source 55 and a test circuit, of means for applying the voltage of said source to said test circuit including a plurality of spark gaps and a thermionic tube for changing the voltage of said gaps.

7. The combination with a high-voltage circuit including a plurality of spark gaps, 65 condensers across said gaps, and means in-

cluding a thermionic tube across one of said gaps for changing the voltage across said gaps for causing said gap to break down.

In testimony whereof, I have hereunto subscribed my name this 23rd day of February, 1929.

RAGNAR TANBERG.
